Nathaniel Baldwin INVENTOR

UNITED STATES PATENT OFFICE

NATHANIEL BALDWIN, OF EAST MILL CREEK, UTAH

LOUD-SPEAKER

Application filed May 17, 1927. Serial No. 192,027.

The present invention appertains to loud speakers and particularly to that class in which a vibrating armature is surrounded by an actuating coil and is acted upon at either end by magnetic poles.

The principal object is to obtain increased efficiency by increasing the number of turns in the actuating coil without increasing its resistance and to diminish the magnetic reluctance by a special design of armature.

I attain this and other objects by the mechanism illustrated in the accompanying drawing in which Fig. 1 is an end elevation of the device, Fig. 2 is a section of the same on the line A-B of Fig. 1, Fig. 3 is an end elevation showing parts cut away; Fig. 4 is a top view showing parts removed, and Fig. 5 is a top view of a special part.

In the several figures of the drawing number 1 designates a U-shaped magnet to the inner pole—faces of which are attached the U-shaped polepieces 2 and 3. These polepieces are formed so that the limbs of one overlap the limbs of the other with a space between for the armature 4, and one limb of the polepiece 2 is below and the other is above the corresponding limbs of the polepiece 3. A spool 5 containing the actuating winding fits in between the limbs of the polepieces and is held in position by the projecting edges 6, 6 and 7, 7 formed upon these polepiece limbs.

The armature 4 which is a special feature of the present invention has a constricted portion which is surrounded by the spool 5 and enlarged ends which are acted upon by the magnetic poles. This permits the use of a spool with a small center and yet provides a comparatively large armature surface to be acted upon by the polepieces.

Having a spool with a small center permits the use of a greater number of turns in the winding without increasing the electrical resistance, and an increase of efficiency is the result.

The spool 5 as shown particularly in Fig. 3 has a slot in one side through which the armature is inserted before winding.

To provide better insulation and to diminish the electrostatic capacity of the wind-

ing, one or more partitions 8 may be provided.

In Fig. 4 the winding on one side of the partition 8 and part of the polepiece 3 are removed to show the position of the armature.

The effective armature 4, as shown in Fig. 5, has an extension part 4^a, which may be a nonmagnetic bar sealed to the armature, or it may be identical and integral with the armature.

The end of the extension part 4^a, remote from the armature, is firmly mounted within the magnet 1 by means of the bracket 9 and the said extension part is given the necessary flexibility by being cut thinner near said bracket.

The acoustic element such as a diaphragm 10 is connected to the armature 4 by means of the link 11.

In the instrument here illustrated the armature has a fulcrum without the spool, but this form of armature can be used with a fulcrum within the spool such as shown in my patent for telephone receiver dated October 26, 1926, No. 1,604,251, it may be used with a fulcrum at both ends of the spool such as shown in Patent No. 1,557,554 dated October 20, 1925, or it may be used with any other support, such as shown in my application for telephone receiver filed August 29, 1925, Serial No. 53,350.

The armature here illustrated has an enlarged or widened portion at each end but the same invention can be applied at one end only if desired.

In the spool as here illustrated the winding is separated by a partition into two coils, but if desired several such partitions could be used.

The improvements, here shown are especially adapted to loud speaker purposes but it is obvious that they can be used in connection with other acoustic devices, such as telephone receivers, telephone transmitters, phonograph recorders, and inductive phonograph reproducers.

I claim:

1. A device of the class described comprising a fixed actuating coil, an armature ex-

tending through said coil, an enlarged portion at each end of said armature, magnetic poles acting upon the enlarged portions of said armature, and an acoustic element operatively connected with said armature.

5. 2. A device of the class described comprising a fixed actuating coil, an armature extending through said coil, an enlarged portion at each end of said armature, U-shaped polepieces inclosing said coil and acting upon the enlarged portions of said armature, and an acoustic element operatively connected with said armature.

10. 3. A device of the class described comprising a spool containing an actuating coil, an armature extending through said spool, an enlarged portion at one end of said armature U-shaped polepieces inclosing said spool and acting upon the enlarged portion of said 15 armature, projecting edges upon said polepieces to hold said spool in position, and an acoustic element operatively connected with said armature.

20. 4. A device of the class described comprising a spool containing an actuating coil, an armature extending through said spool, an enlarged portion at each end of said armature, U-shaped polepieces inclosing said spool and acting upon the enlarged portions 25 of said armature, projecting edges upon said polepieces to hold said spool in position, and an acoustic element operatively connected with said armature.

25. 5. A device of the class described comprising a fixed actuating coil, having a central opening, an armature extending through said opening and having enlarged portions at either end of said armature larger than said opening, magnetic poles acting upon the enlarged portions of said armature, and an acoustic element operatively connected with said armature.

40. 6. In an acoustic device, a fixed actuating coil a laterally vibratile armature extending through said coil, an enlarged portion at each end of said armature, and magnetic poles acting upon said enlarged portions.

45. 7. In an acoustic device, a magnet, a fixed coil disposed in the field of said magnet, and an armature with enlarged ends disposed in said coil, said armature being mounted to vibrate in a direction transverse to the greatest dimension of said enlarged ends.

50. 8. In an acoustic device, a magnet, polepieces contacting said magnet, an actuating coil in said polepieces, an armature disposed to be acted upon by both said coil and said magnet, said armature having an enlarged end, and a support for said armature comprising a resilient member attached at one end to said armature and at its other end to a fixed element.

55. 9. In an acoustic device, a magnet, a coil in operative relation therewith, and an armature with enlarged ends disposed in said coil,

the said enlarged ends being substantially unpolarized when said coil is not energized.

10. In an acoustic device, a magnet, a coil in operative relation therewith, and an armature having enlarged ends mounted to execute arcuate vibrations in said coil transversely to the greatest dimension of said enlarged ends.

70. 11. In an acoustic device, a magnet, a coil in operative relation therewith, and an armature having enlarged ends mounted to execute arcuate vibrations in said coil transversely of the greatest dimension of said enlarged ends, the support of said armature being fulcrumed outside of said coil.

75. NATHANIEL BALDWIN.
